UNITED STATES PATENT OFFICE.

CHARLES R. BIRDSEY, OF HINSDALE, ILLINOIS, ASSIGNOR TO UNITED STATES GYPSUM COMPANY, OF CHICAGO, ILLINOIS, A CORPORATION OF ILLINOIS.

WALL BOARD.

Application filed October 10, 1921. Serial No. 506,675.

To all whom it may concern:

Be it known that I, CHARLES R. BIRDSEY, a citizen of the United States, residing at Hinsdale, in the county of Du Page and State of Illinois, have invented new and useful Improvements in Wall Boards, of which the following is a specification.

The invention relates to improvements in wallboards and more particularly to a wall-board made of plaster with a paper covering.

A distinction has arisen in the trade whereby the term wallboard is applied to prepared board that can be secured in place in a building and its surface is ready to paper or paint without any other coating, while the term plaster-board is applied to a prepared board that is secured to the studding in the place of laths and presents a surface to receive plaster before it is painted or papered.

It is an object of this invention to provide a wallboard the body of which is a composition, preferably plaster, covered on each side with cover sheets, preferably and in so constructing the longitudinal edges of the wallboard that the composition body during manufacture will be retained directly to the edges at a uniform thickness throughout and the cover sheets adjacent the edges so reinforced as to maintain a full straight edge of uniform thickness during transportation and upon application, allowing wallboards to be placed edge to edge uninterrupted by any nailed in such position without disrupting the plaster body between the coverings at the edges.

While the preferred form of this invention is illustrated upon the accompanying sheet of drawing, yet it is to be understood that minor detail changes may be made without departing from the scope thereof.

In the drawing:

Figure 1 is a view in cross-section, with parts broken away, illustrating the construction of the longitudinal edges of a form of this invention.

Figure 2 is a perspective view of Figure 1 illustrating the longitudinal and transverse edges of this improved form of wallboard.

Figure 3 is a detailed view in cross-section illustrating a modified form of edge constructed in accordance with this invention.

Figure 4 is a perspective view of Figure

3 illustrating the longitudinal and transverse edges of this form of wallboard.

Wallboard of this general type is usually constructed continuously in a machine, through which is fed a wide strip of paper which forms the bottom covering upon which the composition is automatically spread and a similar strip of paper forming the upper sheet is fed thereover, the two cover sheets with the composition body between them passing out of the machine between rollers that impart a uniform thickness to the wallboard.

This invention contemplates turning back upon itself, each longitudinal edge of each cover sheet so that the ends are on the inside and the sheets of uniform width.

As shown on the drawing, 1 is the under or bottom cover sheet and 2 the upper or top cover sheet, 3—3 are the bent back portions of the longitudinal edges of the bottom sheet and 4—4 the bent back edges of the upper sheet. This construction gives the cover sheets rigidity to maintain the body 5 continuously to the edge 6 of the wallboard on each side during fabrication, holds the body firmly between them and is reinforced so as to protect and keep intact the body during transportation and application. It is preferable that the bent back portions 3 and 4 be glued or otherwise attached to the inner sides of their respective coverings. The imbedded ends 3 and 4 are turned back sufficiently so that the wallboards may be placed edge to edge with uninterrupted contact and may be secured in place by driving nails through the wallboards adjacent the edges without disrupting the plaster at the edges.

If desired, while in course of manufacture, a cover strip, preferably of paper, 7 may be fed in between the cover sheets 1 and 2 along the exterior of the edges of the body. This strip will become attached to the composition body, form an additional assurance that the body 5 will continue uninterrupted to the edge, and will form an additional protection to the edge during fabrication, transportation and application.

What I claim is:

1. A wallboard having a plaster composition body and upper and lower cover sheets with a reinforcement along each longitudinal edge thereof formed by turning back

the edges of the cover sheets upon themselves.

2. A wallboard having a rigid composition body and upper and lower cover sheets with a reinforcement along each of the longitudinal edges thereof formed by turning back the edges of the cover sheets upon themselves and securing the turned back portions to the bodies of the respective sheets.

3. A wallboard having a plaster composition body and upper and lower cover sheets with a reinforcement along each longitudinal edge thereof formed by turning back the edges of the cover sheets upon themselves on the interior of the board.

4. A wallboard having a rigid composi-

tion body and upper and lower cover sheets with reinforcements along each of the longitudinal edges thereof, formed by turning back the edges of the cover sheets upon themselves on the interior and imbedding the turned back edges in the body.

5. A wallboard having a composition body and upper and lower cover sheets with reinforcements along the longitudinal edges thereof, formed by turning back the edges of the cover sheets upon themselves on the interior, imbedding the turned back edges in the body, and a cover strip attached to the plastic body between the opposite longitudinal edges of the cover sheets.

CHARLES R. BIRDSEY.
